UNITED STATES PATENT OFFICE

2,408,224

CAMPAIGN BADGE

John B. Palmer, Los Angeles, Calif.

Application December 4, 1944, Serial No. 566,440

1 Claim. (Cl. 40—1.6)

1

The present invention relates to new and useful improvements in campaign badges, buttons and the like adapted to be worn and has for its primary object to provide a badge of this character having a window opening therein and a slide mounted in the badge and containing two or more names printed thereon adapted for selective registry with the window opening to interchangeably expose either of said names to view therein.

A further object of the invention is to provide an article of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a front elevational view.

Figure 2 is a vertical longitudinal sectional view through the badge casing taken substantially on a line 2—2 of Figure 3.

Figure 3 is a vertical transverse sectional view taken substantially on a line 3—3 of Figure 1.

Referring now to the drawing in detail and first with respect to the form of the invention illustrated in Figures 1 to 3, inclusive, the numeral 5 designates a badge which includes a front wall 6 and rear wall 7, secured in spaced apart substantially parallel relation to each other by intermediate spacing walls 8 to provide a chamber 9 in the badge.

The front wall 6 is formed with a substantially rectangular window opening 10 and the rear wall 7 is formed with a vertically extending slot or substantially rectangular opening 11.

A panel 12 is slidably mounted in the chamber 9 of the badge having upper and lower strips 13 and 14 cemented in a horizontal position on the front surface of the panel 12, the strips having printed or otherwise displayed thereon suitable printed matter, which in the present embodiment of the invention designate names of different persons 15 and 16, the upper and lower names being selectively exposed in the window opening 10 upon a vertical sliding movement of the panel 12 in the chamber 9.

The back of the panel 12 is provided with a boss or lug 17 slidably mounted in the opening or slot 11 and to the boss or lug is suitably secured a safety pin or other fastening device 18.

2

The front of the badge 5 may also have printed matter 19 suitably displayed thereon by means of gummed strips or printing the same directly on the badge.

Accordingly, in the operation of the device the names 15 and 16 may designate different candidates for election to an office and the wearer of the badge may selectively move the panel 12 so as to bring either of said names into registry with the window opening 10 in accordance with his wishes.

It may be assumed that the panel in the form of my invention is maintained in adjusted position relative to the window by friction between the panel and walled chamber.

By using the names of two or more opposing candidates in a single badge having an adjustable panel therein it is obvious that the same badge may be used by different political parties and therefore under ordinary circumstances only one badge would be needed in stock.

In view of the fact that all of the principal elements or features of my invention are substantially rectangular it appears that the invention would readily lend itself to accurate quantity production.

By the use of adhesive labels which could be readily removed the badge could be used in a multiplicity of different or similar campaigns. A label and its name could be applied to the panel through the window. It will thus be appreciated that the parts of the walled chamber may be permanently secured together with the panel permanently captive therein.

It is believed that the details of construction and manner of use of the device will be readily understood from the foregoing without further detailed explanation.

Having thus described the invention, what I claim is:

40. A badge of the class described comprising front and rear walls maintained in spaced parallel relation by spacing strip walls, said walls defining a rectangular walled chamber, said front wall having a centrally located substantially rectangular horizontal window, said rear wall having a centrally located vertical substantially rectangular opening, in combination with a panel slidably fitted within the major portion of the walled rectangular chamber, said panel having two labels adhesively secured respectively on each side of a centrally located horizontal line on said panel, said labels having indicated thereon respectively the names of opposing candidates for a certain office, said labels and names thereon being indi-

vidually and selectively displayed through the window of the front wall, said panel having on its rear side a centrally located vertical boss extending through the rectangular opening in said rear wall and slidably received therein, cooperating stops on said panel and on said walled chamber to provide for limited movement rela-

tively of said walled chamber and panel, whereby the alignment of either label and its name for display through the window may be accomplished, means on said boss whereby said badge may be secured on a garment for display purposes.

JOHN B. PALMER.
